TOWEL BAR

Raymond U. H. Tegner, Lodi, Wis., assignor to Amerock Corporation, Rockford, Ill.

Filed Nov. 10, 1972, Ser. No. 305,326

Term of patent 14 years

Int. Cl. D6—06

U.S. Cl. D6—99

FIG. 1 is a top view of a towel bar incorporating my new design.

FIG. 2 is an enlarged fragmentary front view of the towel bar.

FIG. 3 is an end view as seen from the left in FIG. 2.

FIG. 4 is a fragmentary sectional view taken along the line 4—4 in FIG. 2.

FIG. 5 is a sectional view taken along the line 5—5 in FIG. 2.

FIG. 6 is a sectional view taken along the line 6—6 in FIG. 2.

FIG. 7 is a sectional view taken along the line 7—7 in FIG. 2.

FIG. 8 is a sectional view taken along the line 8—8 in FIG. 2.

The broken line representation of support brackets in FIG. 1 is for purposes of illustration only.

I claim:

The ornamental design for a towel bar, as shown and described.
